United States Patent Office

Des. 228,786
Patented Oct. 23, 1973

228,786

COMBINACIÓN TAPE PLAYER AND RADIO

George E. Lyall, Melrose, Mass., assignor to Automatic
Radio Mfg. Co., Inc.

Filed Aug. 14, 1972, Ser. No. 280,540

Term of patent 14 years

Int. Cl. D14—01

U.S. Cl. D26—14 B

Fig. 1.

Fig. 2.

Fig. 3.

Fig. 4.

Fig. 5.

FIG. 1 is a perspective view of a combination tape player and radio showing my new design;
FIG. 2 is a side view thereof;

FIG. 3 is a rear view thereof;
FIG. 4 is a bottom view thereof; and
FIG. 5 is a front view thereof.

I claim:

The ornamental design for a combination tape player and radio, substantially as shown and described.
